(57) **CLAIM**

The ornamental design for a cap for bottle, as shown and described.

DESCRIPTION

FIG. 1 is a perspective view of a cap for bottle of the present invention showing our new design;

FIG. 2 is a rear view of the cap for bottle shown in FIG. 1; FIG. 3 is a front view of the cap for bottle shown in FIG. 1; FIG. 4 is a left view of the cap for bottle shown in FIG. 1; FIG. 5 is a right view of the cap for bottle shown in FIG. 1; FIG. 6 is a top view of the cap for bottle shown in FIG. 1; and,

FIG. 7 is a bottom view of the cap for bottle shown in FIG. 1.

In the drawings, the broken lines showing of a cap for bottle depict portions of the cap and form no part of the claim.

1 Claim, 7 Drawing Sheets
